UNITED STATES PATENT OFFICE

2,604,270

MACHINE FOR GRINDING OR REFINING
PAINT, CELLULOSE, CHOCOLATE, AND
OTHER SUBSTANCES

John McIntyre, Portobello, Scotland

Application May 3, 1949, Serial No. 91,164
In Great Britain May 10, 1948

8 Claims. (Cl. 241—102)

1

This invention has reference to machines for grinding or refining paint, cellulose, chocolate and other substances and relates particularly to such machines of the type comprising a cylinder, the inner face of which is provided with stationary longitudinally extending fixed grinding bars, and a rotor mounted on a driven shaft and carrying resiliently loaded longitudinally extending grinding bars, which, when rotated co-operate with the stationary grinding bars.

One object of the invention is to provide improvements in grinding machines of the type set forth whereby a better grinding action will be obtained by the co-operation of the stationary grinding bars and the resiliently loaded grinding bars.

Another object of the invention is to provide improvements whereby the material being ground is fed to the grinding bars.

Preferred embodiments of the invention will now be described with reference to the annexed drawings wherein:

Figure 1 is an elevation of one construction of machine in accordance with the invention, the front cover of the cylinder being removed,

Figure 2 is an end elevation thereof showing the cylinder and upper half of the rotor in section,

Figure 3 shows to a larger scale an elevation of part of the rotor, the ends of two flexible spring bands and the means by which the loading is transmitted to the said two ends,

Figure 4 is an inverted sectional plan view on the line 4—4 of Figure 3 of the said means by which the loading is transmitted to the ends of the spring bands.

Figures 5 and 6 are views corresponding to Figures 1 and 2 respectively of a machine in accordance with the invention but showing alternative means by which the loading can be adjusted, and

Figures 7 and 8 are further views corresponding to Figures 1 and 2 but showing a still further alternative means by which the loading can be adjusted, the aforesaid plates being omitted and only the uppermost and lowermost fixed and rotating grinding bars being shown in Figure 8.

In the various views like reference numerals denote the same or corresponding parts.

As shown in the drawings the improved machine embodies a jacketed cylinder 10 provided with end covers having charging hoppers 11. A suitably located sluice valve or other means, not shown, is provided through which the ground or refined material can be withdrawn. The in-

2

ner surface of this cylinder is formed of lining bars 12 extending from end to end of the cylinder. Said bars, which lie closely adjacent to each other, are provided with rounded inner faces and 5 may be in the form of a lining as set forth in my U. S. A. patent application Serial Number 90,382.

Extending axially into the cylinder is a driving shaft 13 on which is secured a rotor 14 in the 10 form of a wheel having on its periphery open ended radial slots 15, see Figure 3. Said slots are shown arranged in groups at regularly spaced distances apart, but they may extend completely round the rotor or be otherwise arranged.

15 Fitted into said slots are the grinding bars 16, the fit being such that they can partake of a radial movement in the slots.

Said bars may be of any section found suitable; for example they may be of round section, or 20 have flat sides and grinding rounded ends.

The slots are such that the grinding bars fitted 25 therein are so positioned that one end of each is slightly in advance of the other end whereby the said bars impart or aid in imparting a longitudinal flow to the substance being ground or refined in addition to the usual rotary flow.

Carried by the rotor at the rear of each group 30 of bars 16 is a plate 17 lying at such angle to the adjacent bars 16 that it forms therewith a pocket in which the material being ground is caught and 35 from which it passes through the openings between the said bars. Said plates, like the bars, are so set that one end thereof, the leading end, is in advance of the other.

35 Flexible pressure bands 18, conveniently of spring steel, are provided to bear on the inner faces of the grinding bars 16. Each band is formed of two substantially semi-circular segments. To the end of each segment is secured 40 one leaf 19 of a hinge member the other leaf, which may be made of spring steel, constituting a strut 19a. The two struts connected to adjacent ends of the spring segments are mounted on a pivot pin 20 carried by a bracket 21 having two

45 lugs, see particularly Figures 3 and 4. The lugs of the two upper brackets 21 straddle the ends of a cross bar 22, and the lugs of the two lower brackets straddle the ends of a second cross bar 23. Said cross bars, which pass through slots in 50 the rotor, are pivotally connected towards their centres to rods 24 supplied by guide lugs 25 of brackets secured to the rotor.

In the arrangement shown in Figures 1 and 2 the inner ends of the rods 24 are screw threaded 55 as at 26 and nuts screwed thereon bear on the

inner lugs 25. It will therefore be appreciated that by turning said nuts the rods 24 can be moved radially, such motion being transmitted through the cross bars 22 and the struts 19 to the ends of the semi-circular spring bands.

When in use material introduced into the machine is ground by the co-operation of the fixed grinding bars 12 of the cylinder with the groups of rotating bars 16 of the rotor, all of which bars 16 are constantly urged radially outwardly by means of the spring bands 18.

Should it be desired to alter the pressure exerted by the bars 16 or the bars 12 the aforesaid nuts are turned to move the rods 24 radially. When said rods are moved radially outwards the spring bands bear harder on the grinding bars 16 all of which then bear harder on the fixed bars.

Now should the grinding bars carried by the rotor become worn they may be slipped from the slotted wheel and reversed so that the faces which were formerly innermost now become the grinding faces.

Further where it may be necessary to replace said bars the old ones can be slipped out and new ones substituted therefor.

In the construction shown in Figures 5 and 6 the rods 24 are connected by means of links 27 to an internally threaded member 28 threaded on a screw threaded spindle 29. This spindle is provided at one end thereof with a head which fits within a recess in the end of the shaft 13, a retaining plate 30 on the end of the shaft preventing relative longitudinal movement of the spindle. The other end of this spindle has fast thereon a disc 31 provided with two holes therein. Arranged to engage with the said holes are pins 32 carried by a disc 33 fast on a spindle 34. The latter is in axial alignment with the shaft and its outer end, which extends through the front cover of the cylinder, is provided with a hand wheel 35.

To alter the pressure exerted by the bars 16 or the bars 12 the spindle 34 is moved axially inwards to bring the said two pins into register with the holes in the disc 31. Spindle 34 is then rotated and a corresponding movement transmitted to the screw spindle 25 so that the member 28 is caused to travel towards or away from the rotor. The movement of said member is transmitted through the links 27 so that the rods 24 are moved radially. The rods in turn through the cross bars and struts and spring bands increase or decrease the pressure exerted by the rotating grinding bars on the fixed bars.

In the arrangement shown in Figures 7 and 8 the rods 24, which are screw threaded at their inner ends, can be forced outwards to increase the pressure exerted between the co-operating grinding bars by means of two opposed rams 36 located within a cylinder 37 to which fluid can be injected by means of a manually operated plunger 38 which works within a cylinder 39. When fluid is forced into the cylinder 38 the rams are forced apart and the rods 24 in turn are forced radially outwards to increase the pressure between co-operating grinding bars. When the rods are forced apart to impart the requisite pressure they may be locked in such position by means of nuts threaded on the screw threaded ends thereof, said nuts bearing on the inner lugs 25.

I claim:

1. A machine of the type set forth having a rotor provided with open ended radial slots, grinding bars fitted in said slots so as to be capable of

an outward radial movement therein and at least one resilient flexible band bearing on said bars and urging them outwardly in and with respect to their slots.

5. A machine of the type set forth having a rotor provided with open ended slots, grinding bars fitted in said slots so as to be capable of a radial outward movement therein, at least one flexible band extending circumferentially of and within the rotor, said band being formed of arcuate sections and bearing on said bars, and means connected to the adjacent free ends of the arcuate sections by which the sections are urged outwards.

15. 3. A machine of the type set forth having a rotor provided with open ended radial slots, grinding bars fitted in said slots so as to be capable of a radial outward movement therein, at least one resilient flexible band bearing on said bars to urge them outwardly in their slots and plates carried by the rotor and positioned radially inward from the said bars, the leading edge of each plate being further from the bars than the trailing edge so that, when the machine is in use, 20 the material being ground is trapped and guided between the grinding bars by the said plates.

25. 4. A machine of the type set forth having a rotor provided with open ended radial slots, grinding bars fitted in said slots, two resilient bands formed of arcuate sections and bearing on said bars, radial rods carried by the rotor and capable of radial adjustment, cross bars carried by the outer ends of said radial rods, a pair of strut members secured to each end of each cross bar and adjacent ends of two of said arcuate sections and means by which the radial rods can be adjusted radially to regulate the pressure exerted by the bands on the bars.

30. 5. A machine of the type set forth having a rotor provided with open ended radial slots, grinding bars fitted in said slots, two resilient bands formed of arcuate sections and bearing on said bars, radial rods carried by the rotor and capable of radial adjustment, cross bars carried by the outer ends of said radial rods, and a pair of resilient steel strut members secured to each 35 end of each cross bar and to adjacent ends of two of said arcuate sections and means by which the radial rods can be adjusted radially to regulate the pressure exerted by the bars.

35. 6. A machine of the type set forth having a rotor provided with open ended radial slots, grinding bars fitted in said slots, two flexible bands formed of arcuate sections and bearing on said bars, radial rods carried by the rotor and capable of radial adjustment, cross bars carried by the outer ends of said radial rods, a pair of strut members secured to each end of each cross bar, each pair being connected to adjacent ends 45 of two arcuate sections, and means by which said rods can be adjusted radially to regulate the force by which the said bars are urged outwards.

40. 7. A machine of the type set forth having a rotor provided with open ended radial slots, 50 grinding bars fitted in said slots, two flexible bands formed of arcuate sections and bearing on said bars, radial rods carried by the rotor and capable of radial adjustment, cross bars carried by the outer ends of said radial rods, a pair of strut members secured to each end of each cross bar, each pair being connected to adjacent ends 55 of two arcuate sections, a screw threaded spindle in axial alignment with the axis of the rotor and mounted for free rotation with respect 60 to the rotor, a collar screwed on said spindle,

links connecting said collar to the radial rods and manually operable means to rotate the spindle so that the collar is moved axially thereon to regulate the pressure of the bands on the bars.

8. A machine of the type set forth having a rotor provided with open ended radial slots, grinding bars fitted in said slots, two flexible bands formed of arcuate sections and bearing on said bars, radial rods carried by the rotor and capable of radial adjustment, cross bars carried by the outer ends of said radial rods, a pair of strut members secured to each end of each cross bar, each pair being connected to adjacent ends of two arcuate sections, a pair of opposed cylinders, pistons working in said cylinders and bearing on the inner ends of the radial rods and

means by which fluid under pressure can be supplied to the two cylinders to force the pistons radially outwards.
